(57) CLAIM

The ornamental design for an art display reinforcing member, as shown and described.

DESCRIPTION

FIG. 1 is an exploded isometric view of an art display reinforcing member;

FIG. 2 is a top view of the art display reinforcing member of FIG. 1 in position within the art display;

FIG. 3 is a front view of the art display reinforcing member shown in FIG. 2, which is a mirror image of the back view (not shown);

FIG. 4 is a left side view of the art display reinforcing member shown in FIG. 2, which is a mirror image of the right side view (not shown); and,

FIG. 5 is a bottom view of the art display reinforcing member shown in FIG. 2.

The even-broken lines in FIG. 1 illustrate release liners that are removable from the art display reinforcing member and form no part of the claimed design. The dot-dash-dot lines illustrate an art display that is to receive the art display reinforcing member and form no part of the claimed design.
